ELECTROMAGNETIC SWITCH

Theodore J. Wilson, Minneapolis, Minn., assignor
to Minneapolis-Honeywell Regulator Company,
Minneapolis, Minn., a corporation of Delaware

Application January 3, 1950, Serial No. 136,458

10 Claims. (Cl. 200—91)

1

This invention relates to electromagnetic switching devices and more particularly to the type known as vibrators. The prime object of this invention is to provide an improved vibrator design which is compact and rugged in construction and reliable in operation.

It is further an object of this invention to provide a simplified vibrator design which is easy to assemble and maintain, and capable of carrying substantial currents and withstanding rough usage.

Another object of this invention is to provide an improved contact structure for a device of this type which is simple to construct and assemble and maintain in adjustment.

Other objects and advantages reside in the details of construction which will become apparent upon reference to the accompanying specification, claims and drawing. For a better understanding of these objects, however, and the specific objects obtained by the present invention, reference should be had to the accompanying drawings, wherein:

Figure 1 is a plan view of the vibrator disclosing the subject invention,

Figure 2 is a side elevation view of the subject vibrator,

Figure 3 is an end elevation view of Figure 2 (in section) of the subject vibrator disclosing the relationship of parts,

Figure 4 is a schematic view of the vibrator to disclose relationship of parts, and

Figure 5 is a sectional view of the vibrating reed with the electrical connections thereto.

Figure 1 of the drawings shows a polarized electromagnetic vibrator embodying the principles of the present invention in which an armature 10 is mounted to move or vibrate under the influence of a plurality of unidirectional magnetic fields created by a pair of permanent magnets 11 and a pulsating or alternating field imposed on one end of the armature 10 adjacent the magnets 11, the latter or pulsating field being created by an electrical winding 12 energized from an alternating current source of power.

The improved vibrator design of the subject invention is characterized by its simple yet rugged construction, the component parts of which are carried by a frame member 13 generally rectangular in form and having a longitudinally extending slot 14 therein of varying cross-section. Frame member 13 is made of a suitable non-magnetic material which can be either metallic or non-metallic. However, to provide a

2

frame member capable of withstanding wear and abuse, it has been found satisfactory to use a metal such as brass or aluminum. Slot 14 in frame member 13 is suitably formed, such as by machining or molding to provide the varying dimensions or cross-sections therein. One extremity of slot 14 is substantially reduced in width, as at 16, and is designed to fit or accommodate a root or shank 20 of armature 10 for the purpose of securely attaching the armature to the frame and permitting pivotal movement of the same. The root or shank 20 has an aperture therein (not shown) through which the armature is secured to the frame by means of a bushing 21 inserted in an aperture 22 in the side of frame member 13, the bushing being clamped against the root or shank by means of a screw 23 threaded into the frame member. Screw 23 is designed to fit into the frame member and secure the bushing in such a manner that it is recessed from the surface of the frame member to eliminate any projecting part.

Armature 10 is generally reed-like in form being made of a flexible and non-magnetic material having a uniform cross-section except for the shank 20 and a notched end portion 24. Within the notches 24 in the end of reed or armature 10 is positioned a pair of plates of magnetic material 25 to form a magnetic end for an otherwise non-magnetic armature. The plates 25 are attached to the reed or armature 10 by any suitable means such as rivets, and the plates are of such thickness that in assembled relationship this end of the reed has substantially the same cross section as the remaining portion of the reed with the exception of the shank. These magnetic plates 25 on the end of reed 10 are positioned between pole extremities 27, 28 of a pair of permanent magnets 11 which provide the unidirectional magnetic fields for the vibrator. The magnets 11 are generally U-shaped in form as seen in Figure 4 and are fitted into transversely extending slots in the end of the frame member opposite the mounting of the reed, the slots connecting with the longitudinally extending slot 14 such that the pole extremities 27, 28 terminate in the longitudinally extending slot and are positioned in near abutting relationship. Magnets 11 are further so positioned in this end of the frame member that the opposite or unlike polarity ends of the magnets are positioned adjacent one another to define a pair of air gaps 32, 33 through which the magnetic portion of the reed, that is the plates 25, extend. The air gaps 32, 33 so

formed by the location of the magnets are of such dimension that the armature or reed is permitted limited pivotal or transverse movement between the pole extremities thereof. Slot 14 in frame member 13, as previously noted, was not uniform throughout its extent, and as will be seen in the drawings, is considerably enlarged at the extremity of the frame member containing the permanent magnets. Within this enlarged portion, indicated at 35, is located the winding 12 which is mounted on an insulating spool 37 encircling the end of the reed or armature carrying the magnetic plates 25. Winding 12 is so shaped that it fits within the opening 35 so formed and lies between the bifurcated portions of the permanent magnets 11 and the pole extremities 27, 28. Mounted on spool 37 through notches 40 therein are a pair of lead wire holders 41 to which holders the ends of the coil 12 are extended. An external source of power, not shown, is connected to the coil through suitable leads shown at 43 which connect to the turns of the winding at the extremities thereof mounted on the holders 41. If desired the in leads may be brought out from the vibrator frame through a suitable aperture 44 therein such that the external connections to the in leads may be made from below the base of the frame. An insulating strip 46, as is shown in Figures 1, 2 and 3, is disposed above the coil and frame to insulate the connections from the cover element 50 enclosing this portion of the frame 13. The cover is connected to the end of the vibrator frame 13 by means of screws such as are shown at 52. As was noted above, winding 12 is adapted to be energized from an A. C. source of power such that the extremities of the magnetic plate 25 on armature 10 have imposed thereon magnetic polarities which alternate with the alternation or variation in current flow through the winding. The consequent attraction and repulsion between the poles formed in the magnetic plates and the poles of the permanent magnet cause vibration of the armature or reed 10 in a well known manner.

Armature reed 10, as it vibrates under the influence or interaction of the magnetic fields, operates a contact structure, the movable portion of which is carried by reed or armature 10 within the longitudinally extending slot 14 of frame 13. This movable portion of the contact structure includes a pair of flexible contact blades 61 with contact members 62 mounted thereon, as by riveting or soldering, both the blades and the contact members being made of an electrically conductive material. Blades 61 are attached to reed or armature 10 by a plurality of rivets 63 and are insulated from the reed or armature 10, the rivets 63 and one another by strips of insulation 64 and insulating bushings 65, as can be seen in Figure 4. Rivets 63 perform the function of holding the insulating materials in position and rigidly securing one extremity of the blades 61 to the reed 10 with the free extremity of the blades which carry the contacts 62 disposed substantially parallel to the reed. Free extremities of blades 61 are held in a slightly biased or flexed relationship by means of a blade catch 66 of insulating material mounted on blade or armature 10. The blade catch 66 is grooved or notched as at 67 to receive the ends of the contact blades 61 during assembly and flex the blades to a slightly biased condition in a manner well known in the art of vibrators. The grooves 66 are suf-

ficiently large such that movement of the end of the blades therein permits suitable flexing of the blades upon contact with the stationary portion of the contact structure later to be described. To accommodate such movement of the blades 61 and the contacts 62 thereon, an aperture 70 is provided in reed or armature 10 such that the portion of the contact 62 adjacent the reed will not contact the reed proper upon flexing of the contact blade. Aperture 70 permits such clearance for both contact structures 62.

The movable portion of the contact structure at the contact 62 is designed to engage stationary portion of the contact structure which is mounted on frame 13, this stationary portion including contact blocks 72 slidably positioned in transversely extending slots 73 in frame member 13 which slots communicate with the longitudinal slot 14 of the frame member. Each of the contact blocks 72 are made of a suitable electrically conductive material and have an aperture 74 therein which is slotted as at 75, the aperture being tapped and designed to receive a threaded contact pin 76 which is fitted to the contact block and extends into proximity with one of the movable contacts 62 of the flexible blades 61 of the movable contact structure. The contact pins 76 are designed to be adjustably positioned within the blocks 72 to fix or adjust the spacing between the movable and stationary portions of the contact structure. The blocks 72, one of which is positioned on either side of the movable contact structure, are insulated from the frame member 13 by means of an insulating member 77, also movable within the slot 73.

The contact blocks 72, insulating members 77 and the contact pins 76 after being positioned within frame 13 and relative to one another are rigidly held in position in frame member 13 in the slots 73 by means of L-shaped clamping members 80 positioned on the frame 13 by means of pins 81 which extend through a receiving aperture 82 in said member. An adjustable locking type screw member 83 extending through an aperture (not shown) in clamping member 80 and threading into the frame member 13 exerts a downward force on clamping member such that the extremity in contact with the insulating member on contact block 72 holds the block in a fixed and rigid relationship with the frame member. In addition, the clamping member 80 further exerts a force on the portions of the contact blocks 72 surrounding the contact pin 76, and by virtue of the slot 75 therein, is able to clamp the pin 76 in a rigid relationship with respect to the block after adjustment has been made to the same.

Electrical connections to the contact block and hence the pins 76 are made by attaching leads to a contact block (not shown) by suitable means, such as soldering. Such leads, as are shown on 85, can be brought out through suitable apertures in the end of the frame member and can be connected in a circuit as desired. Similar connections, as shown at 86, are made to the ends of the flexible contact carrying blade members 61 and such connections may also be brought out through the frame member to one end of the frame member. The contact structure as shown provides for independent circuits through the individual contact carrying blades and stationary contact members formed by the contact pins and contact blocks.

No common connection between these component parts of the contact structure 60 is shown herein but such connection can be made remote from the vibrator.

In operation, the subject vibrator is similar to conventional vibrating devices. Energization of the winding 12 sets up the pair of poles at the extremities of the magnetic plates 25 attached to the reed or armature 10. These poles alternate with the variation or alternation in current supplied to winding 12 and react with the unidirectional fields or poles set up by the magnets 11 to be attracted by one pair and repulsed by another as the polarity of the reed or armature changes. In the present arrangement of permanent magnets, an increased magnetic attraction between armature and magnets is attained to provide for greater force of vibration and hence increase the capacity from the vibrator. The contact elements mounted on the reed and frame members will alternately engage and disengage as the armature or reed is vibrated to complete or break the circuit through the respective contact carrying members and stationary contacts. With the present construction a substantially increased current carrying capacity for the vibrator is obtained and an arrangement is provided by which accurate adjustment may be made to the contact structure which will be maintained throughout the normal operation of the device despite continued usage. Further, if it should become necessary to adjust the contact structure, such adjustment can be made with ease.

In considering this invention it should be kept in mind that the present disclosure is intended to be illustrative only and the scope of the invention is to be determined only by the appended claims.

I claim as my invention:

1. In a vibrator, a non-magnetic frame member having a pair of slots at one end thereof, a pair of U-shaped permanent magnets mounted in said pair of slots in one end of said frame member and disposed with opposite polarity extremities of said magnets in near abutting relationship to define a pair of air gaps therebetween, a non-magnetic vibrating reed member mounted at one extremity in the other end of said frame member and disposed with its free extremity in said air gaps, a pair of plates of magnetic material mounted on said free end of said flexible reed and disposed adjacent the extremities of said permanent magnets, a coil encircling said free end of said reed and said plates of said magnetic material, said coil being positioned in an aperture in said frame member and between the extremities of said magnets and being adapted to be energized with an alternating source of power to magnetize said plates with alternating polarities such that said reed is attracted to the extremities of said magnets to cause vibration of said reed, and contact means mounted on said reed and insulated therefrom, said contact means cooperating with stationary contacts adjustably mounted within said frame and insulated therefrom, the vibration of said reed upon energization of said coil causing alternating engagement of said contact means and said stationary contacts.

2. In a vibrator, a non-magnetic frame member, a pair of U-shaped permanent magnets mounted in one end of said frame member and disposed with opposite polarity extremities in near abutting relationship to define a pair of

air gaps therebetween, a non-magnetic reed member, said reed having an increased dimension at one extremity which fits into a slot in said frame member removed from said permanent magnets, means including a screw means for rigidly mounting said reed within said slot, said free extremity of said reed having notches therein and being disposed in said gap between said magnets, a pair of plates of magnetic material positioned in said notches in said reed and attached thereto being disposed to move with said reed within said air gaps, a coil encircling said free end of said reed and said plates of magnetic material, said coil being positioned in an aperture in said frame member and between the extremities of said magnet and adapted to be energized with an alternating source of power whereby said plates are magnetized with alternating polarities such that said reed is attracted to the extremities of said magnets to cause vibration of said reed, and contact means mounted on said reed and insulated therefrom, said contact means cooperating with stationary contacts adjustably mounted within said frame and insulated therefrom, the vibration of said reed upon energization of said coil causing alternating engagement of said contact means and said stationary contacts.

3. In a vibrator, a non-magnetic unitary frame member having a longitudinal slot and a pair of transversely extending slots therein, a pair of U-shaped permanent magnets mounted in said transversely extending slots in one end of said frame member and disposed with opposite polarity extremities in near abutting relationship to define a pair of air gaps therebetween, a flexible reed positioned in said longitudinal slot and secured at one extremity to said frame member having a locus of pivot remote from said magnets with the free extremity of said reed disposed within said air gaps, magnetic means mounted on said extremity of said reed within said air gaps, an energizing winding positioned within said frame and between said magnets encircling said magnetic means and adapted to be energized from an alternating source of power whereby said magnetic means is magnetized and attracted between the extremities of said magnets to cause vibration of said reed, and contact means mounted on said reed and insulated therefrom, said contact means cooperating with stationary contacts adjustably mounted within said frame and insulated therefrom, the vibration of said reed upon energization of said winding causing alternating engagement of said contact means in said stationary contacts.

4. In a vibrator, a non-magnetic frame member, a pair of U-shaped permanent magnets mounted in one end of said frame member and disposed with opposite polarity extremities in near abutting relationship to define a pair of air gaps therebetween, a non-magnetic reed member, said reed having an increased dimension at one extremity which fits into a slot in said frame member removed from said permanent magnets, means including a screw means for rigidly mounting said reed within said slot, said free extremity of said reed having notches therein and being disposed in said gap between said magnets, a pair of plates of magnetic material positioned in said notches in said reed and attached thereto being disposed to move with said reed within said air gaps, a coil encircling said free end of said reed and said plates of magnetic material, said coil being positioned in an

aperture in said frame member and between the extremities of said magnet and adapted to be energized with an alternating source of power whereby said plates are magnetized with alternating polarities such that said reed is attracted to the extremities of said magnets to cause vibration of said reed, and contact means including a first contact member attached to said reed and a second contact member attached to said frame, said contact means being adapted to be operated upon vibration of said reed.

5. In a vibrator, a non-magnetic frame member having a longitudinally extending slot therein, a pair of U-shaped permanent magnet members positioned in transversely extending slots in one end of said frame member and extending into said longitudinally extending slot positioned with the extremities of said magnet in near abutting relationship, a flexible reed of non-magnetic material positioned in said longitudinally extending slot and rigidly secured to said frame member at the opposite extremity from said magnets, said reed at its free end being positioned between the ends of said permanent magnet, magnetic means mounted on said reed between said magnets, a coil encircling said free end of said reed and said magnetic means and positioned within an aperture in said frame between the extremities in said magnet, said coil being adapted to be energized from a source of alternating current to magnetize said magnetic means with opposite polarities such that said reed is attracted between the extremities of said magnets to cause vibration of said reed, and contact means including a first contact member attached to said reed and a second contact member attached to said frame, said contact means being adapted to be operated upon vibration of said reed.

6. In a vibrator, a non-magnetic frame member having a longitudinally extending slot therein, a pair of U-shaped permanent magnet members positioned in transversely extending slots in one end of said frame member and extending into said longitudinally extending slot with the extremities of said magnets in near abutting relationship, a flexible reed of non-magnetic material positioned in said longitudinally extending slot and rigidly secured to said frame member at the opposite extremity from said magnets, said reed at its free end being positioned between the ends of said permanent magnet, magnetic means mounted on said reed between said magnets, a coil encircling said free end of said reed and said magnetic means and positioned within an aperture in said frame between the extremities in said magnet, said coil being adapted to be energized from a source of alternating current to magnetize said magnetic means with opposite polarities such that said reed is attracted between the extremities of said magnets to cause vibration of said reed, a pair of flexible contact carrying members mounted on and insulated from said reed, and stationary contact members mounted on said frame member, said stationary contact members including mounting blocks slidably positioned in a second pair of transversely extending slots in said frame member with contacts adjustably positioned therein.

7. In a vibrator, a non-magnetic frame member having a longitudinally extending slot therein, a pair of U-shaped permanent magnet members positioned in transversely extending slots in one end of said frame member and extending into said longitudinally extending slot with the

extremities of said magnet in near abutting relationship, a flexible reed of non-magnetic material positioned in said longitudinally extending slot and rigidly secured to said frame member at the opposite extremity from said magnets, said reed at its free end being positioned between the ends of said permanent magnet, magnetic means mounted on said reed between said magnets, a coil encircling said free end of said reed and said magnetic means and positioned within an aperture in said frame between the extremities in said magnet members, said coil being adapted to be energized from a source of alternating current to magnetize said magnetic means with opposite polarities such that said reed is attracted between the extremities of said magnets to cause vibration of said reed, a pair of flexible contact carrying members mounted on and insulated from said reed, stationary contact members mounted on said frame member, said stationary contact members including mounting blocks slidably positioned in a second pair of transversely extending slots in said frame member with contacts adjustably positioned therein, means insulating said blocks from said frame member, and means adjustably securing said blocks to said frame member.

8. In a vibrator, a non-magnetic frame member having a longitudinally extending slot therein, a pair of U-shaped permanent magnet members positioned in transversely extending slots in one end of said frame member and extending into said longitudinally extending slot with the extremities of said magnet in near abutting relationship, a flexible reed of non-magnetic material positioned in said longitudinally extending slot and rigidly secured to said frame member at the opposite extremity from said magnets, said reed at its free end being positioned between the ends of said permanent magnets, magnetic means mounted on said reed between said magnets, a coil encircling said free end of said reed and said magnetic means and positioned within an aperture in said frame between the extremities in said magnet, said coil being adapted to be energized from a source of alternating current to magnetize said magnetic means with opposite polarities such that said reed is attracted between the extremities of said magnets to cause vibration of said reed, a pair of flexible contact carrying members mounted on and insulated from said reed, stationary contact members mounted on said frame member, said stationary contact members including mounting blocks slidably positioned in a second pair of transversely extending slots in said frame member with contacts adjustably positioned therein, means insulating said blocks from said frame member, and means adjustably securing said blocks to said frame member, said last named means rigidly securing said contacts within said contact mounting blocks.

9. In a device of the class described, a non-magnetic frame member having a longitudinally extending slot therein, a pair of permanent magnets positioned in one end of said frame member in a pair of transversely extending slots with the extremities of said permanent magnets in near abutting relationship, a non-magnetic reed positioned in said longitudinally extending slot, means including a screw means for securing one extremity of said reed within the extremity of said slot remote from said magnets such that the free extremity of said reed is located between the free extremities of said magnets, magnetic

means mounted on the free extremity of said reed between said magnets, an energizing winding encircling said reed and said magnetic means positioned between said permanent magnets within said frame member, a flexible contact means mounted on said reed, stationary contact means mounted on said frame member and including a mounting block slidably positioned in a second transversely extending slot in said frame member, second contact means including a contact pin adjustably positioned within said contact block, means insulating said contact block from said frame member, and means adjustably securing said contact block to said frame and said contact pin within said contact block.

10. In a device of the class described, a non-magnetic frame member having a longitudinally extending slot therein, a pair of permanent magnets positioned in one end of said frame member in a pair of transversely extending slots with the 20 extremities of said permanent magnets in near abutting relationship, a reed member positioned in said longitudinally extending slot, means including a screw means for securing one extremity of said reed within the extremity of said slot remote from said magnets such that the free extremity of said reed is located between the free extremities of said magnets, said reed member

including a magnetic portion at the free extremity of said reed between said magnets, an energizing winding encircling said reed positioned between said permanent magnets within said frame member, a flexible contact means mounted on said reed, stationary contact means mounted on said frame member and including a mounting block slidably positioned in a second transversely extending slot in said frame member, second contact means including a contact pin adjustably positioned within said contact block, means insulating said contact block from said frame member, and means adjustably securing said contact block to said frame and said contact pin within said contact block.

THEODORE J. WILSON.
